FUSE PLUG

Filed Dec. 19, 1923

Inventor:
Otto H. Van Amburg;
by *Alvanda S. Last*,
His Attorney.

UNITED STATES PATENT OFFICE.

OTTO H. VAN AMBURG, OF BRIDGEPORT, CONNECTICUT, ASSIGNOR TO GENERAL ELECTRIC COMPANY, A CORPORATION OF NEW YORK.

FUSE PLUG.

Application filed December 19, 1923. Serial No. 681,606.

The present invention relates to thermal safety devices for electric circuits and more especially to reloadable fuse plugs.

The object of my invention is the provision of an improved fuse plug in which the fusible element may be renewed with facility without the use of tools and which may be manufactured at low cost.

One embodiment of the invention is shown in the accompanying drawing in which Fig. 1 is a vertical section of a complete plug; Fig. 2 is a similar section of the insulating top with the side contact attached thereto; Fig. 3 is a similar section of the inner insulating tube with the fusible element in position; Fig. 4 is a similar section of the insulating bottom shell with the center contact attached thereto, and Fig. 5 is a perspective view showing method of assembly of certain parts.

The side contact 1 is a metal cylinder with a closed upper end 2 and an open lower end with the usual screw thread 3 formed in the lower portion of the cylinder, while between the threaded portion and the upper end the cylindrical wall 4 is provided with pairs of longitudinal slits 5 and the metal bridges 6 between them forced inwardly to provide yieldable friction means to be referred to below.

The upper end of the side contact cylinder 1 is enclosed by an insulated handle portion in the form of a porcelain cap 7 and the two parts are permanently connected by a circular contact plate 8 having integral arms 9 which pass through holes 10 in the upper end 2 of the side contact shell and corresponding holes 11 in the top of the insulating cap 7 and are clenched over the bottom of a mortise 12 extending from the outer surface of the cap part way through the top wall thereof. After the arms 9 are clenched over, the mortise 12 is filled with cement 13.

The insulating bottom shell 14 is of porcelain with its upper end open and an end wall 15 provided at its lower end through which the center contact 16 extends. The side wall cylindrical and of a diameter to bear lightly against the inner surfaces of the bridge pieces 6 when it is introduced into the side contact shell 1. Notches 17 are formed in the periphery of the lower end to provide a good hand hold. The center contact 16 is in the form of a stud with a

large head 18 seated against the interior surface of the end wall 15 and its shank 19 extending therethrough and headed over a washer 20 on the outer surface thereof.

The support for the fusible element is in the form of an inner insulating tube 21 of tough material such as horn fiber and is cylindrical with both ends open. The diameter of the tube 21 is sufficiently small to permit it to be assembled with clearance in the bottom shell 14 and its length is such that when so assembled its upper end projects slightly above the upper end of the bottom shell.

The fusible element 22 is preferably of the form shown and described in the Weston Patent 1,441,550, January 9, 1923, but any other approved form may be used. It is assembled by threading through the bore of the inner tube 21 and crimping over the opposite ends thereof.

The inner tube 21, with the fusible element 22 in position, is dropped into the cavity of the bottom shell 14 and the latter inserted in the side contact shell 1 where it is frictionally held by the engagement of the bridges 6 with the outer surface thereof, but capable of being readily detached without the use of tools. When the assembled plug is screwed home in the ordinary cutout block or receptacle, the lower shell 14 will be forced inwardly of the side contact shell 1 and ensures good contact between the ends of the fusible member 22 and the center contact 16 and the contact plate 8 respectively.

When the fusible element 22 becomes blown or disrupted, the gases evolved become cooled as they come in contact with the extended inner and outer surfaces of the inner tube 21, the inner and outer surfaces of the lower shell 14, and the inner surface of the side contact shell 1, so that upon escaping from the latter they are harmless.

While I have shown and described the best embodiment of the invention known to me, I do not desire to be restricted thereto.

What I claim as new and desire to secure by Letters Patent of the United States, is:

1. A fuse plug comprising an insulated threaded side contact shell, a lower shell of insulation provided with a center contact and adapted to be telescopically assembled detachably within said side contact shell, a longitudinal bridge on said contact shell adapted to frictionally retain said lower

shell therein, and a fusible element support adapted to be assembled detachably within said lower shell and to support the ends of the fusible element in engagement with said side contact shell and said center contact.

2. A fuse plug comprising a threaded cylindrical side contact shell having one end closed, an insulating handle attached to the closed end of said shell, a lower shell provided with a center contact, means to telescopically receive and frictionally retain said lower shell within said side contact shell, and a tubular support for the fusible element adapted to be assembled within said lower shell and to support the ends of the fusible element in engagement with said center contact and the closed end of said side contact shell.

3. A fuse plug comprising a tubular side

contact shell having one end closed, an insulating cap surrounding said closed end, a contact plate engaging the inner surface of said closed end and having clench extensions therefrom passing through and anchoring said side contact shell to said cap, a lower shell of insulation having one end closed and provided with a headed center contact, frictional means for holding said lower shell within said side contact shell, and a tube of insulation adapted to be assembled within said lower shell and to support a fusible member in engagement with said contact plate and said headed center contact.

In witness whereof, I have hereunto set my hand this 13th day of December 1923.

OTTO H. VAN AMBURG.
